W. Field,

Oliver

Patented Sept. 14, 1833.

July 31, 1833

33.

William Field of North Providence State of Rhode Island

Letters Patent.)

The schedule referred to in these Letters Patent and making part of the same containing a description in the words of the said William Field himself of his improvement called the upright spring storage hammer.

To all persons to whom these presents shall come,
Be it known that I, William Field of North Providence in the County of Providence, in the State of Rhode Island and Providence Plantations, mechanist, have invented a new and useful machine called the upright spring storage hammer, and that the following is a full and exact description of the construction and operation of the said machine as invented by me, it consists of a platform of sufficient weight and size for the required number of hammers. The frame is composed of two posts, ~~one~~ side into the platform, standing upright, the distance from each other to depend on the number of hammers required, each hammer requiring about thirteen inches in length, also two back posts standing so far in the rear of the first named as to admit the machinery hereafter in this specification described. The front and rear posts are connected together each by a cap, and between the front and rear posts is framed in at each end a girt.

The hammers are made of cast or wrought iron, in the lower end of each is a square, or round hole to receive the necessary face and dies for drawing and bending iron or steel, in its various shapes, and sizes, directly under each hammer is placed an anvil block and anvil having on the top a hole matching with the one in the hammer, above to receive a corresponding face or dies of pleasure, the hammers and anvils are held for the purpose of bending out the faces, or dies of pleasure, the hammers in operation move up and down on an iron plate or base running from one front post to the other, to which the plate or base are made fast by bolts, the hammer may blow on the plate or base, and are confined that to by iron stops, friction rollers & bolts.

The hammer is set in motion by a staff or cylinder running longitudinally from one end of the frame to the other or long or lever, on the first in the rear of the hammer having on its surface a wheel, which striking similar projections on the hammer, causes the hammer to strike. The blow or stroke is given by the hammer after the cog, being it by its own weight and a staff made of wood iron or steel placed on the upper end of the hammer, and is forced down upon the hammer by a lever which is operated by the foot of the workman standing in front of the machine. The upstroke lever is connected with the spring by an iron rod, and the workman is able to give the hammer any force he chooses, by pressing down the lever. The hammer is stopped when the staff or cylinder is in full motion, at the pleasure of the workman, by a spring & catch placed on the main plate by the side of the hammer, which catch is forced into a notch on the hammer by said spring, and holds the hammer up while stopped. To put the hammer in motion the spring and catch are drawn back by an iron rod running from the catch to the lever, by means of which the hammer may be stopped or put in motion by the foot of the workman upon the lever at any time.

The above described machine may be operated by water, steam or horse power, and may be used for all the purposes of the trip hammer over which it possesses many important advantages.

I claim a ^{1756X} patent as the inventor of said machine, and for applying it to the purpose of blacksmithing, for the construction and form of the hammer, for the plan of putting in the face and dies, for the plan of holding the hammer up when stopped by a spring and catch, for the manner of connecting the hammer to the main complete or body by staff, piston rods and bolts, for the manner of giving the blow by the staff and lever, connected by an iron rod at the pleasure of the workman for the plan of drawing back the catch and setting the hammer in motion, for the manner of taking out the face, and dies and for being able to put four faces to one hammer into the space generally occupied by one trip hammer.
